PROCESS AND MACHINE FOR VACUUM
BOTTLE TUBULATING AND PIERCING

Charles Eisler, South Orange, N. J.

Application October 7, 1949, Serial No. 126,105

4 Claims. (Cl. 49—1)

1

The object of the invention is to provide means for practically simultaneously tubulating and piercing the outer blank of a vacuum bottle, the tubulated glass tube serving as a means for subsequently exhausting the vacuum space between inner and outer blanks of the assembled and sealed vacuum bottle.

A further object of the invention is to provide a machine having novel means for holding the blank and tube in abutment and for serially subjecting the same to operations at stations of the machine to complete the tubulating and piercing operation, as hereinafter more fully set forth.

In the drawings:

Fig. 1 is a top plan view of a machine embodying the invention, showing the sequence of operations, the positions of operation being serially indicated by Roman numerals I—XII, inclusive,

Fig. 2 is a partially sectional, elevational view of a machine embodying the invention, provided with non-rotatable heads,

Fig. 3 is an elevational view showing the piercing operation,

Fig. 4 is a fragmentary, vertical, partly sectional view, showing the exhaust tube positioned in its holder, in working contact with the bottom of the blank, as in the loading position I of Fig. 1,

Fig. 5 is a fragmentary, schematic view, showing the first step in the process of fusing the tube to the blank prior to piercing,

Fig. 5A is a schematic view of parts shown in Fig. 5, showing their form upon continued application of heat,

Fig. 6 is a similar view of the parts subjected to the piercing operation,

Fig. 7 is a similar view of the parts in the operation of glazing the pierced aperture, and

Fig. 8 is an elevational view, showing the means employed for tubulating and piercing in a rotating head.

In Fig. 1 of the drawings, the machine is shown provided with a plurality of heads, the number and disposition of which may be varied within the spirit and scope of the invention. The sequence of operations, designated by Roman numerals in Fig. 1, is:

- I. Loading
- II. Pre-heating
- III. Pre-heating
- IV. Heating
- V. Heating
- VI. Tubulating and internal heating of blank
- VII. Piercing and glazing
- VIII. Annealing
- IX. Annealing

2

X. Annealing
XI. Cooling
XII. Unloading.

5 The machine comprises (see Figs. 1 and 2) the table 10 having legs 11, and a spider 12 secured to the vertical shaft 13, and periodically rotated by an indexing device, such as "Geneva" wheel 14, driven by pawl 15, mounted on vertical shaft 16 to which is keyed the wormwheel 17 rotated by wormwheel 18 on shaft 19. Shaft 19 is preferably driven through reduction drives 20 and 21 by motor 22. Any other indexing device, such as barrel cam-intermittent gearing or the like, may be employed, if desired.

10 The tubulating heads may be either of the non-rotatable (Fig. 3) or of the rotatable (Fig. 8) type, the choice being governed generally by the size and diameter of the blank and the wall thickness, the rotatable type of head being generally deemed best suited to large blanks of thick glass. If rotatable heads are employed, corresponding additions and modifications may be readily made in the driving mechanism, such as are shown in 15 some of the machines previously patented by me—see, for example, Patent 2,413,960 of January 7, 1947.

Fig. 3 shows a machine having a non-rotative head. The exhaust tube 24 which is to be tubulated to the bottom wall of the blank 23 of 20 U-shaped cross-section has (at the loading position I) been inserted into the bore 25 of the tube holder 26 (Fig. 4), the tube holder having the threaded plug 27 having the head 28 for adjusting depth of the insertion. The tube holder 26 25 is adjustable, as by setscrew 29, on the post 30 mounted in the spider 12. The threaded plug 27 has the axial airhole 31 terminating in the conical mouth 32 for admission of a blast of compressed air during the piercing (Fig. 6) operation. When the exhaust tube 24 is in place, the blank 23 is inserted into the open retaining collar 33 of blank retainer bracket 34 which is slidable on the post 30 and provided with setscrew or similar means to engage the post to fix its position thereon. The blank is moved downwardly 30 until it rests atop the exhaust tube, as shown in Fig. 4. After loading, the blank passes serially to positions II, III, IV and V, where it is preheated and heated by burners 35 and 36.

35 At position VI, inside heating of the bottom of the blank is effected by the vertical burner 37 to which a gas mixture is fed by duct 38 and the flexible tube 39 which is connected to mixer 40 (Fig. 2) of the gas, oxygen and air ducts 41, 42, 43, supplied from an outside source by pipes 41a,

42a, 43a (Fig. 1). Vertical gas duct 38 is secured by bracket 44 to the vertical shaft 45 slideable in support 46, and is raised and lowered by any desired or convenient means, such as the lever 47 fulcrumed in bracket 48 (Fig. 2), the end 47' of the lever being disposed in following engagement with barrel cam 49 on wormwheel shaft 16. Any other means for actuating shaft 45 may be employed, such as a compressed air device, which would have the advantage of eliminating the barrel cam and lever. On raising shaft 45, the gas duct 38 and the burner 37 may be entirely withdrawn from the blank 23, as indicated in dotted lines in Fig. 3.

At position VI (Fig. 5), the vertical burner 37 is lowered into the blank 23 and the inside bottom of the blank is heated, the outside thereof being kept hot by burners 50. The flame from burner 37 heats the tubulation juncture T and makes a weakened cavity (66, Fig. 5a) which may be fractured to define an opening 65 in the bottom of the blank communicating with the tube 24, or punctured as hereinafter set forth, the bottom wall of the blank being weakened (or rendered very plastic at least, at 66). The blank then passes to position VII where the flame from the burner 37 is partially turned off and a blast of air is passed through the duct 31 in plug 27 and so through the exhaust tube and the bottom of the glass blank, thus perforating it at 65 as shown in Fig. 6. As soon as the blast of air is shut off—by means of economizer 51—the flame of burner 37 effects the glazing of the perforation 65 and its first annealing. Complete annealing of a large blank would best be effected by a third, similar device, at position VIII, but, with a small blank, this would not be necessary and outside annealing by burners 50 is found to be sufficient. At positions VIII, IX, X, further annealing is effected by burners 52; the tubulated blank is then allowed to cool at position XI and is unloaded at position XII.

The rotating form of head is shown in Fig. 8 wherein the bracket 54 is shown provided with posts 53 on which are adjustably mounted the open blank retainer brackets 55 and the tube holder 26. The bracket 54 is keyed to the sleeve shaft 56 which is rotatable on the hollow shaft 57 provided with duct 58 for the passage of compressed air from the supply duct 59. The bracket 54 is rotated by means, such as the cone pulleys 60 and 61, rotation being stopped at the loading and unloading positions by the head stop 62 engaging the stop rail 63; the cone pulley 61 is driven by the suitable means, such as the sprocket and chain transmission 64. The device shown in Fig. 8 for raising and lowering the internal burner may be the same as the correspondingly numbered parts shown in Fig. 3 for the non-rotatable head.

The drawings show a machine having a table provided with a spider for rotating the parts to the various stations; it will be appreciated that the invention may be used with equal efficacy in machines embodying a straight line or any other non-rotary assembly plan.

Having thus described my invention, what I claim as new and desire to secure by Letters Patent is:

1. In a machine for tubulating an exhaust tube having open ends to the lower end of a blank of U-shaped cross-section to be used for forming a vacuum bottle, an open retaining collar adapted to receive the blank and hold the same vertically with the closed end thereof lowermost, a tube holder to hold the tube in abutment with the lower end of said blank, means for heating the bottom of said blank internally and for externally heating the same, to fuse the same to the tube and seal the same at the point of abutment therewith and to form a cavity in the bottom of said blank depending into said tube, and means for passing a pressure agent through said tube to pierce the said cavity to form an aperture at the tubulating juncture of said tube and blank.

2. The method of tubulating an exhaust tube having open ends to the lower, closed end of a blank U-shaped cross-section, which consists in vertically disposing the U-shaped blank with its closed end lowermost, positioning the exhaust tube vertically therebelow in abutment with the closed end of the blank, heating the closed end of the tube internally and heating the exhaust tube and said closed end at their abutment areas to fuse the same and to weaken the closed end of the tube in that portion thereof enclosed by said fused portions to form a weakened cavity depending downwardly into the tube, and discontinuing the heating of the tube and closed end at their abutment areas and reducing the heating of the tube internally and simultaneously passing a blast of air through the tube and against the weakened cavity to perforate the same.

3. In the method of tubulating an exhaust tube having lower ends to a closed end of the blank having a U-shaped cross-section, as set forth in claim 2, an additional step comprising discontinuing the supply of the blast of air through the exhaust tube and increasing the internal heating of the blank to effect glazing of the perforated area and subsequently annealing the tube and blank at their fused areas.

4. In the method of tubulating an exhaust tube having lower ends secured to a closed end of the blank, having a U-shaped cross-section as set forth in claim 2, an additional step comprising discontinuing the supply of the blast of air through the exhaust tube and heating the blank interiorly at the perforated area to effect glazing thereof.

CHARLES EISLER.
